SLIDING SHELF

Richard J. Carberry, Syracuse, N. Y., assignor to General Electric Company, a corporation of New York

Application February 19, 1954, Serial No. 411,462

5 Claims. (Cl. 312—338)

My invention relates to sliding shelves and more particularly to sliding shelf arrangements adapted for use in refrigerator cabinets or the like.

One of the most common instances of sliding shelf arrangements are those vertically spaced shelves ordinarily provided in household refrigerating apparatus. Sliding shelves are, of course, needed there in order to provide easy access to food stuffs stored in the rear portion of the refrigerated cabinet. With those shelves heretofore available, however, a problem has been presented by the variations in the spacing of the cabinet side walls which quite often occur in mass production. Since the shelves have been supported by studs mounted on the cabinet walls, the variation in spacing of the walls has often resulted in binding of the shelves against the studs so as to interfere with their sliding movement. Although this binding can be alleviated by hand bending of the side walls, by changing the mounting of the studs, or by other suitable means, nonetheless such is an expensive procedure where a mass production item is involved.

Accordingly it is a primary object of my invention to provide within a refrigerator cabinet a new and improved sliding shelf arrangement including means allowing for variation in the spacing of the cabinet walls.

It is another object of my invention to provide a new and improved sliding shelf arrangement in which the shelf rests on but is not attached to the sliding means.

A further object of my invention is to provide a sliding shelf arrangement for refrigerator cabinets which is less expensive to fabricate and assemble than those arrangements heretofore available.

In carrying my invention into effect, I provide a refrigerator cabinet having a rear wall, oppositely disposed side walls, and a forward access opening. Within this cabinet separate track or guide members are attached to each of the side walls. Slidably supported by each of those track members is a movable bar which is provided with inwardly extending projections adjacent the ends thereof. The shelf itself is removably supported by these projections. In order to provide for the sliding movement thereof the shelf includes means which positively engage each of the bars, whereby a force applied to the shelf is transmitted to the bars. The result is movement of the bars within their track members and thus sliding movement of the shelf itself into or out of the cabinet. This sliding movement will not be affected by variations in the spacing between the side walls since the projections on which the shelf rests allow for variations in the spacing between the opposite track members and bars without the shelf rubbing or binding thereagainst. Preferably the positive engagement between the shelf and bars necessary for the sliding movement is accomplished through the manner of contact between the shelf and the projections.

The novel features which I believe to be characteristic of my invention are set forth with particularity in the appended claims. My invention, however, both as to its organization and method of operation, may be best un-

2

derstood by reference to the following description taken in conjunction with the accompanying drawing in which:

Fig. 1 is a fragmentary view of the upper portion of a refrigerator cabinet including a sliding shelf arrangement embodying my invention;

Fig. 2 is an enlarged perspective view, partially broken away, of a preferred embodiment of my sliding shelf arrangement; and

Fig. 3 is a fragmentary vertical view in partial section illustrating the manner in which the sliding shelf rests upon its supporting structure.

Referring now to Fig. 1 I have illustrated therein the upper portion of a refrigerator cabinet including an outer metal wall 1 and an inner metal wall or liner 2, the space between the walls being filled with a suitable heat-insulating material. The walls are formed to provide an access or door opening 3 at the front of the cabinet, and the space between the walls in the area of the door frame is closed by a breaker strip 4 of suitable heat insulating material. The liner 2 forms the food storage compartment of the cabinet and is shaped to provide a rear wall and oppositely disposed side walls, only side wall 5 being shown. The compartment is refrigerated by a standard refrigerant evaporator 6 and is closed by a suitable door (not shown).

Within the compartment 2 there is mounted a sliding shelf arrangement which embodies my invention in one preferred form thereof. As may be best seen in Fig. 2 this shelf arrangement includes a pair of track or guide members 7 and 8 which are affixed respectively to the opposite side walls of the liner 2. Any suitable means, as for example the screws 9, may be used to accomplish this mounting. Within these track or guide members are mounted the movable or sliding means on which the sliding shelf is supported and in order to accommodate these sliding means the tracks 7 and 8 are preferably formed, as shown, in a more or less channel-shaped configuration. However, it should be understood that various other shapes of track members could be used.

In my preferred embodiment the sliding means accommodated by the track members comprise the rod or bar members 10 and 11, the bar 10 being received within track member 7 and the bar 11 within track member 8. The fit between the bars and the track members is loose enough that the bars may be readily slid in and out. However, to facilitate this sliding movement I have provided bearing or glider members which space the bars and the track members somewhat from each other and greatly reduce sliding friction therebetween. Thus adjacent their front ends channel-shaped gliders 12 and 13 are mounted respectively on track members 7 and 8; and adjacent their rear ends plate shaped gliders 14 and 15 are mounted respectively on bars 10 and 11. These gliders may be formed of any suitable material as for example nylon.

In order that they may support a shelf the bar members are each provided adjacent their ends with inwardly extending projections or tabs. Thus at their forward ends the bars 10 and 11 are provided respectively with bent-back sections 16 and 17 which terminate respectively in the inwardly extending tabs 18 and 19. Similarly at their rear ends the bars 7 and 8 are provided respectively with inwardly extending projections 20 and 21 of a U or channel-shaped configuration.

In the illustrated embodiment the shelf supported from these projections comprises the shelf 22 formed of transverse front and rear frame members 23 and 24, wires or rods 25 extending between the frame members, and a reinforcing center transverse member 26. Specifically in my illustrated embodiment the front frame member 23 comprises a trim piece but it should be understood that such a decorative member is not necessary to my invention.

Various means could, of course, be used to support a shelf, such as shelf 22, from the projections 18 and 19 and 20 and 21 of the bar members 10 and 11; but in my preferred embodiment this support is provided through the front and rear frame members 23 and 24 of the shelf. By so using the frame members an inexpensive, easily fabricated shelf is accomplished. Specifically the front frame member 23 rests on the top of the projections 18 and 19 while the rear frame member 24 is received in interlocking relation by the channel-shaped projections 20 and 21, as clearly shown in Fig. 3. The rear frame member 24 as shown is channel-shaped but it should be obvious that it could have other suitable shapes so as to be accommodated by the channel-shaped projections 20 and 21.

Although when the shelf 22 is placed in position on the bar projections, it merely rests thereon not being attached thereto in any way, nonetheless, in my preferred embodiment the above-described relationship between the rear frame member 24 and the channel-shaped projections 20 and 21 provides a positive engagement between the shelf and the bar members permitting a sliding force applied to the shelf to be transmitted to the bar members.

Since the rear frame member 24 rests within the rear projections 20 and 21 a horizontal force applied to the shelf and thus to member 24 will be transmitted through the upstanding sides of the projections to the bars 10 and 11. Further since the bars 10 and 11 as mentioned above, slide freely within the tracks 7 and 8, therefore a force applied to the shelf 22 will result in the bars and the shelf sliding together outwardly or inwardly in the cabinet. The relation between the bearings or gliders 12 and 13 mounted on the track members and the bearings or gliders 14 and 15 mounted on the bars provide an outward limit for this sliding movement. When the bars and the shelf have been pulled sufficiently outward, the bearings 14 and 15 move into engagement with the bearings 12 and 13 and prevent any further forward movement.

As well as providing an easy friction free sliding movement and a ready removal of the shelf from its supports, this shelving arrangement also provides allowance for variation in the spacing of the liner side walls. Since the frame members or other supporting means 23 and 24 of the shelf rest on projections of the bar members 10 and 11, any variation in spacing of the side walls will be taken up by these projections. In other words enough space is left between the ends of the frame members and the bar members so that even if the side walls are closer together than normally, the frame members or other supporting means will still not come into contact with the bars or the track members. In the perfect liner the frame members or other shelf supporting means lie far enough out on the bar projections so that room is left to accommodate them without binding when variations in side wall spacings do occur in the production process.

With reference to the manner in which the shelf is supported on the bar projections 18 and 19 and 20 and 21, the positive engagement for sliding movement has been described, as shown in the diagram, between the rear frame member 24 of the shelf and the rear projections 20 and 21 of the bar members. It should be obvious, however, that this positive engagement could be provided at the front of the shelf and bar members rather than at the rear if so desired; and in fact could be provided through different interlocking means than the cooperating channel-shaped projections and frame member shown. The illustrated manner has, however, been found to be effective in operation and inexpensive to manufacture.

In addition to its feature of obviating the difficulty heretofore caused by variations in the spacing of the liner walls, my sliding shelf arrangement also has the advantage that a single shelf structure 22 can be used throughout the refrigerator either as a sliding shelf or as a stationary shelf where both are used, thereby effecting savings in manufacturing costs. For sliding shelves, the structure

22 would be removably mounted on my novel track and sliding bar construction as described above, and for stationary shelves the same structure would be affixed to pins or studs extending from the liner wall. This allows a saving in both tooling and assembly costs relative to such costs when different constructions are used for the sliding and stationary shelves, as has been the case heretofore.

5 In accordance with the patent statutes I have described what at present is considered to be the preferred embodiment of my invention. However, it should be obvious to those skilled in the art that various changes and modifications may be made therein without departing from my invention, and I, therefore, aim in the appended claims 15 to cover all such changes and modifications as fall within the true spirit and scope of my invention.

What I claim as new and desire to secure by Letters Patent of the United States is:

1. In a refrigerator cabinet having a rear wall and oppositely disposed side walls, a sliding shelf arrangement 20 comprising track members attached to said side walls, movable bars slidably supported by said track members, each of said bars having inwardly extending projections adjacent the ends thereof, at least one of said projections 25 of each of said bars being channel-shaped, and a shelf removably supported by said projections, said shelf including means received by said channel-shaped projections to effect a positive engagement between said shelf and said bars whereby sliding movement of said shelf is effected by movement of said bars within said track members, each of said bars being independent of the other and being connected together for movement only by said shelf.

2. In a refrigerator cabinet having a rear wall and oppositely disposed side walls, a sliding shelf arrangement 30 comprising track members attached to said side walls, movable bars slidably supported by said track members, each of said bars having inwardly extending projections adjacent the ends thereof, the rear of said projections on each of said bars being channel-shaped, and a shelf removably supported by said projections, said shelf including a rear frame member received by said channel-shaped projections to effect a positive engagement between said shelf and said bars whereby sliding movement of said shelf is effected by movement of said bars within said track members, each of said bars being independent of the other and being connected together for movement only by said shelf.

3. In a refrigerator cabinet having a rear wall and oppositely disposed side walls, a sliding shelf arrangement 35 comprising channel-shaped track members attached to said side walls, movable bars slidably received by said track members, each of said bars having inwardly extending projections adjacent the ends thereof, the rear of said projections of each of said bars being channel-shaped, and a shelf resting on said projections and removable therefrom, said shelf including a rear frame member received by said channel-shaped projections to effect a positive engagement between said shelf and said bars whereby sliding movement of said shelf is effected by movement of said bars within said track members, each of said bars being independent of the other and being connected together for movement only by said shelf.

4. In a refrigerator cabinet having a rear wall and oppositely disposed side walls, a sliding shelf arrangement 40 comprising track members attached to said side walls, movable bars slidably supported by said track members, each of said bars having inwardly extending projections adjacent the ends thereof, bearing means for facilitating the sliding movement between said bars and the associated track members including a front bearing element attached to each of said tracks and a rear bearing element attached to each of said bars, and a shelf removably supported by said projections, said shelf including means positively engaging at least one projection on each of said bars whereby 45 sliding movement of said shelf is effected through move-

ment of said bars within said track, with said rear bearing elements contacting said front bearing elements to limit the outward extent of said movement, each of said bars being independent of the other and being connected together for movement only by said shelf.

5. In a refrigerator cabinet having a rear wall and oppositely disposed side walls, a sliding shelf arrangement comprising track members attached to said side walls, movable bars slidably supported by said track members, each of said bars having inwardly extending projections adjacent the ends thereof, at least one of said projections of each of said bars being channel-shaped, bearing means for facilitating the sliding movement between said bars and the associated track members, including a front bearing element attached to each of said track members and a rear bearing element attached to each of said bars and a shelf removably supported by said projections, said shelf

10

15

including means received by said channel-shaped projections to effect a positive engagement between said shelf and said bars whereby sliding movement of said shelf is effected by movement of said bars within said track members, with said rear bearing elements engaging said front bearing elements to limit the outward extent of said movement, each of said bars being independent of the other and being connected together for movement only by said shelf.
